WEARING APPAREL AND METHOD OF
CONSTRUCTION

Emanuel J. Pleet, Baltimore, Md.

Application January 20, 1950, Serial No. 139,557

7 Claims. (Cl. 2—236)

1

This invention relates to wearing apparel and is more particularly concerned with garments, such as trousers, skirts and similar items.

An important use of the invention is in the field of trousers and for this reason it will be described hereinafter and illustrated in reference to trousers although it is to be understood that it is also applicable to other types of wearing apparel.

Popular forms of trousers are those which are provided with vertical pleats at the front on either side of the center. The usual construction comprises a pair of spaced pleats on each side of the center, the primary or inner pleat of each pair, that is the one closer to the center of the trousers, being substantially longer than the outer or secondary pleat. In ordinary types of construction the upper end of the pleats terminates at the bottom of the waist band and belt loops are sewed to the waist band above the pleats. In other types of construction, such as that disclosed in U. S. Patent No. 2,477,938, a separate waist band is not provided and concealed tunnels for the belt are placed behind the trouser wall. In this type of construction, the inner or primary pleat is not only ornamental, but is functional to the extent that a portion of it is used to provide the front opening of the tunnel. However, in none of the trousers of the previous types does the outer or secondary pleat serve a functional purpose. Their presence is, in general, ornamental only.

In the pleated form of trousers, the inner or primary pleat is sometimes positioned so as to face the center of the trousers and sometimes to face the side pockets, the latter being usually preferred.

It is an object of this invention to provide trousers of the type mentioned in which both the inner and outer pleats are functionally utilized, without detracting from their ordinary ornamental appearance by fabricating them in such a way that a belt loop or tunnel is an integral part thereof, thus obviating the need for the ordinary separate belt loops and tunnels that are sewed to the trousers.

Another object of this invention is to provide trousers of the type mentioned that utilize the inner and outer pleats thereof in the manner explained and in which the primary pleat may be disposed in a position facing either the center or the side pocket of the trousers.

A further object of the invention is the saving of materials in manufacturing trousers of the

2

type mentioned and of other manufacturing costs.

A still further object of the invention is the provision of trousers having box pleats on the front thereof, the folds of which are so constructed and arranged as to provide belt loops and at the same time permit the folds of the pleats to be positioned in different ways.

These and other objects and advantages of this invention will be apparent from the following description considered together with the accompanying drawing, in which:

Fig. 1 is a front view of the upper portion of a pair of trousers constructed in accordance with an embodiment of this invention.

Fig. 2 is an oblique section along the line 2—2 of Fig. 1.

Fig. 3 is a partially exploded oblique view of a portion of the upper part of the embodiment showing the manner in which a pair of pleats and a belt loop integral therewith are formed.

Fig. 4 is a front view of the portion shown in Fig. 3 with the pleats fully opened or extended showing the cut lines and folds.

Fig. 5 is a view similar to Fig. 1 of a modification of the embodiment illustrated therein.

Fig. 6 is a section along the line 6—6 of Fig. 5.

Fig. 7 is a partially exploded oblique view of a portion of the upper part of the modified embodiment showing the manner in which a pair of pleats and a belt loop integral therewith are formed.

Fig. 8 is a front view of the portion shown in Fig. 7 with the pleats fully opened or extended showing the cut lines.

Fig. 9 is a view similar to Figs. 7 and 8 illustrating the cuts and folds of an alternate modification.

Fig. 10 is a section along the line 10—10 of Fig. 5.

Referring with more particularity to the drawing in which like numerals designate like parts, the embodiment illustrated in Figs. 1, 2, 3 and 4 comprises an ordinary pair of trousers 11 having two vertical box pleats on the front wall on either side of the center thereof. Each box pleat comprises an inner or primary fold 12 nearer the center and an outer or secondary fold 13 nearer its corresponding side pocket. Each box pleat is formed with its folds behind its web 14, the inner longitudinal edges 15 and 16 of the folds abutting each other at the upper part of the pleats to form the rear wall of the pleat. The remaining portions of the folded material project rearwardly to the front wall 17 of the trousers behind the

pleat web 14 and are cut vertically from the top to separate the upper portion of the pleats from the front wall of the trousers a distance sufficient to permit the entrance of a belt 18 therebetween with allowance being made for edge binding at the top, said portions as thus cut providing two flaps 19 and 20 on the inner ends of the rear wall of the pleats which are secured together and flaps 21 and 22 on the front wall of the trousers which are reversed, that is disposed behind the front wall of the trousers which are reversed, that is disposed behind the front wall of the trousers, as indicated by the arrows in Fig. 3, and sewed together in that position. The upper edges of the pleats are then folded over with the upper edge 23 of the trousers and secured together to the usual lining ordinarily provided.

Fig. 4 illustrates the lines of cuts and folds, the folds being indicated in dotted lines and the cuts in full lines, when the pleat is fully opened.

The modification illustrated in Figs. 5, 6, 7 and 8 is for the purpose of reversing the direction of the inner or primary pleats. Some individuals prefer this type of pleat because of the forwardly offset effect it gives at the front of the trousers which tends to conceal a bulging waist line. In this modification, the box pleats are first formed as described in the embodiment previously described with inner and outer folds 24 and 25. A vertical cut 26 is then made adjacent the inside loop of the primary fold in both the back wall of the pleat and the front wall 27 of the trousers behind the pleat web 27A. At the bottom of this vertical cut, a horizontal cut 28 is then made outwardly to the outside loop 29 of the primary fold, or the edge of the web, leaving a double strip 30 which is swung rearwardly 180° to a position behind the front wall of the trousers, as shown in Fig. 7. A second vertical cut 31 is then made at the inside loop of the secondary fold to complete the separation of the upper part of the pleat from the front wall of the trousers. Pieces of material 32 and 33 are then sewed to corresponding cut edges of the folds to bridge the gaps left by the strip 30 in the rear wall of the pleat and the front wall of the trousers, respectively.

The lines of cuts and folds for this modified form are illustrated in Fig. 8, the folds being indicated in dotted lines and the cuts in full lines.

The upper edges of the pleats and strip 30 are then folded over together with the upper edges 31a of the trousers and secured to the usual lining material. The strip 30 thus serves to support the outer edge of the primary pleat in its reversed position and prevents it from sagging.

An alternate modification comprises forming the pleats and integral belt loop or tunnel as described and shown in Figs. 1, 2, 3 and 4 and then cutting the primary pleat horizontally along a line just below the vertical cut together with a portion of the front wall to free the lower portion of the fold entirely from the upper portion, then reversing the said lower portion and securing it in position by any suitable means, which may include an added vertical strip similar to the strip 30. The material would be cut and folded along lines illustrated in Fig. 9. This alternate modification obviates the need for lining materials 32 and 33 since no gap would be effected at the back of the pleats or in the trouser wall. However, if the pleats are made deep enough at their upper parts to provide

sufficient material for the purpose, the modification of Figs. 5, 6, 7 and 8 may be made without the need for any of the lining material 32 and 33, since the corresponding cut edges can be made to overlap each other for the purpose of securing them together even after the strip 30 is removed.

The pleated construction hereinbefore described may be considered as being formed of pleats having front, rear and intermediate plies, with vertical extensions and flaps arranged to provide the belt loops. For example, the lower portion of member 27A of Figs. 5, 6 and 7 would constitute the front ply of the inner pleat which is continuous with and in substantially the same plane as the rear ply of the outer pleat (the one closest to the side pocket of the trousers). The upper part of the member 27A would constitute a vertical extension of the front ply of the inner pleat having edge portions turned inwardly and secured together by insert piece 32. The insert piece 33 may be considered as connecting a vertical extension of the rear ply of the inner pleat and a flap of a vertical extension of the front ply of the outer pleat underlying the upper part of the member 27A.

Having thus described this invention, I claim:

1. The method of manufacturing a pair of trousers having pleats and belt loops integral therewith, comprising forming a box pleat across the waist region of the trousers with the folds of the pleat behind the pleat web, cutting a portion of the folds to provide an opening for the reception of a belt, securing corresponding cut edges of the folds resulting from said cutting together behind the web, separating the lower portion of one of the folds of the pleat from the upper portion thereof, reversing the position of said lower portion relative to the upper portion and securing it in said reversed position.

2. The method of manufacturing a pair of trousers having pleats and belt loops integral therewith, comprising forming a box pleat across the waist region of the trousers with the folds of the pleat behind the pleat web, separating a portion of one of the folds to provide an opening for the reception of a belt, separating the other fold by an L-shaped cut to provide a pair of separate flaps at the waist region and a reversible fold beneath said flaps carrying a vertical strip thereabove, reversing said reversible fold 180° from its original position and securing it in its reversed position by means of said strip.

3. A pleated construction for garments comprising a section of material having a pair of parallel pleats defining a first pleat and a second pleat, each of said pleats having a front ply, an intermediate ply and a rear ply, the front ply of the first pleat being in substantially the same plane and continuous with the rear ply of the second pleat, the rear ply of the first pleat having a vertical extension, the front ply of the second pleat having also a vertical extension and a flap extending toward the vertical extension of the first pleat and underlying the vertical extension of the front ply of said first pleat, said flap and said vertical extension of the first pleat being secured together, the front ply of the first pleat having also a vertical extension with edge portions turned inwardly and secured together to form a belt loop.

4. A pleated construction for garments comprising a section of material having a pair of parallel pleats defining a first pleat and a sec-

ond pleat, each of said pleats having a front ply, an intermediate ply and a rear ply, the front ply of the first pleat being in substantially the same plane and continuous with the rear ply of the second pleat, the rear ply of the first pleat having a vertical extension, the front ply of the second pleat having also a vertical extension and a flap extending toward the vertical extension of the first pleat and underlying the vertical extension of the front ply of said first pleat, an insert piece between and secured to said flap and said vertical extension of the first pleat, the front ply of the first pleat having also a vertical extension with edge portions turned inwardly and secured together to form a belt loop.

5. A pleated construction for garments comprising a section of material having a pair of parallel pleats defining a first pleat and a second pleat, each of said pleats having a front ply, an intermediate ply and a rear ply, the front ply of the first pleat being in substantially the same plane and continuous with the rear ply of the second pleat, the rear ply of the first pleat having a vertical extension, the front ply of the second pleat having also a vertical extension and a flap extending toward the vertical extension of the first pleat and underlying the vertical extension of the front ply of said first pleat, an insert piece between and secured to said flap and said vertical extension of the first pleat, the front ply of the first pleat having also a vertical extension with edge portions turned inwardly and secured together to form a belt loop.

6. A pleated construction for garments com-

prising a section of material having a pair of parallel pleats defining a first pleat and a second pleat, each of said pleats having a front ply, an intermediate ply and a rear ply, the front ply of the first pleat being in substantially the same plane and continuous with the rear ply of the second pleat, the rear ply of the first pleat having a vertical extension, the front ply of the second pleat having also a vertical extension and a flap extending toward the vertical extension of the first pleat and underlying the vertical extension of the front ply of said first pleat, an insert piece between and secured to said flap and said vertical extension of the first pleat, the front ply of the first pleat having also a vertical extension with edge portions turned inwardly, an insert piece between and secured to said edge portions.

7. A pleated construction as defined by claim 3 in which the intermediate and rear plies of the second pleat have a vertical extension attached to an upper part of the garment for supporting said plies.
